DIAL TUNING DEVICE

Edwin G. Bradshaw, Chicago, Ill., assignor to
Wells-Gardner & Company, Chicago, Ill., a cor-
poration of Illinois

Application October 4, 1937, Serial No. 167,222

5 Claims. (Cl. 74—10)

An object of this invention is to provide an improved and simplified form of tuning device of the general type now referred to as telephone dial tuners. Such a tuner has a relatively large tuning dial which is operatively connected to a tuning condenser of a radio receiving set so that as the dial is turned it will rotate a gang condenser which controls a plurality of stages of tuned radio frequency.

10 A telephone dial of this character has a series of depressions each one of which more or less roughly corresponds to a setting of the condenser for a given radio broadcasting station when said depression is brought to a predetermined position of the dial, usually its lowermost position.

It is an object of the present invention to simplify a dial tuner of this type and at the same time to render the tuning of a given station rapid and accurate.

15 These and other objects, as will hereinafter appear, are accomplished by this invention, which is fully described in the following specification and shown in the accompanying drawing, in which:

20 Fig. 1 is a partial front elevation of a radio receiving set showing one form of a dial tuner embodying the present invention;

Fig. 2 is a partial vertical section on the broken line 2—2 of Fig. 1 showing the connection between the dial tuner and the gang condenser which it controls with an operator's finger in place in the first step of roughly tuning a desired station;

Fig. 3 is a similar view showing the operator's hand completing the tuning operation by means of a fine adjusting knob;

Fig. 4 is a front elevation of the same; and

Fig. 5 is a view similar to Fig. 3 showing a modified form of the device in which the fine adjustment is performed by the operator's index finger while in the depression in the tuning dial.

The embodiment illustrated in Figs. 1 to 4 comprises a radio receiving set having a chassis frame 10 above which is mounted in any desired manner, not herein shown, a metal frame 11 in which is suitably journaled a shaft 12 of a gang condenser 13. A gear 14 on the shaft 12 meshes with a pinion 15 (preferably having slightly more than one-half of the number of teeth of the gear 14) on a sleeve 16 which is rotatably mounted on a stud 17 secured at 18 to the frame 11.

The sleeve 16 carries at its forward end a spider 19 which is firmly secured thereon so as

to rotate therewith. This spider has spaced arms 19^a and has on its periphery a dial of Bakelite or the like 20 having a series of depressions 21 all preferably at an equal distance from the center. One of these has been omitted to permit insertion of a zero mark showing the ends of the swing of the disc, and a stop 20^a is supplied at this point. It will be noted that the bottom of each one of the depressions 21 carries a disc 22 and is held in place and protected by means of a disc 23 of a clear transparent material such as Celluloid which also provides a smooth bearing for the operator's finger. If these become scratched or worn, they can readily be replaced. Each disc 22 may be marked with the call letters of a desired radio broadcasting station whose position is nearest that of that particular depression when the latter is at the bottom of its swing as shown in Figs. 1 and 2.

A knob 24 is mounted on a shaft 25, the latter being rotatably and slidably mounted in suitable bearings as 11^a and 11^b in the frame 11. The shaft 25 is provided with a collar 26 secured thereto and pressed normally against the bearing 11^b by means of a compression spring 27. The knob 24 is provided with a rubber washer 28 or the like which is adapted to bear against the outer circular edge of the casting 20.

A usual hand tuning knob 29 is likewise journaled in the frame 11 and has a sheave 30 acting through a flexible wire drive 31 with a sheave 32 on the sleeve 16 for manually tuning the radio set in a well known manner.

The front of the radio set includes an annular escutcheon 33 which overlies the outer edge of the greater portion of the casting 20 so as to properly finish the same.

The center of the dial 20 is open to receive a disc 34 which is opaque and graduated on its outer portion while the inner portion 35 is transparent. This disc is retained by a snap ring 36. Back of the transparent center lies an opaque plate 37 which is supported on the stud 18. It is opaque except for the transparent arrow 38 which serves as a marker for the graduated scale 39 on the disc 34. A translucent sheet of paper or the like 39 is placed inside the arms of the spider to diffuse the light and thus prevent shadows being cast thereby when the dial is illuminated by lamps 40.

The operation of this device is as follows: with the tuning dial having depressions some of which are marked with the call letters of the station to which they correspond, the operator selects one such station which he desires to tune. He

then inserts his finger in that particular depression and turns the disc until that depression as 21^a is at the lowermost position as shown in Figs. 1 and 2. This he can determine even in the dark 5 by the fact that his finger in this position is resting on the top of the knob 24. It may happen that in this position the dial will be sharply tuned. If so, he can withdraw his finger and permit the set to stand in that position. If, however, he desires to tune the set more sharply, he will withdraw his finger, as shown in Fig. 3 10 and use his hand which is already set to grasp the knob 24 to press the latter in until the rubber washer 28 engages the circular periphery of the casting 20 at which time he can slowly turn 15 the knob 24 until the set is sharply tuned in for that desired station. Owing to the fact that the knob 24 is much smaller than the diameter of the casting 20, this tuning can be very delicately done. Thus with a little practice the operator gets to know that for a given station he can swiftly turn the dial down to the lowermost position with his index finger, and as he does so, grasp the knob 24 with his thumb and 20 second finger and quickly tune the set sharply for that station.

In Fig. 5 is shown a modified form of the device in which a tuning knob 24^a is mounted on a shaft 25^a which is rotatable but which does not 30 drive a dial 19^a except through the agency of the operator's finger. Thus having brought the set quickly to a roughly tuned position, the operator by keeping his finger in the depression 21^b as shown in Fig. 5 can do the fine tuning while he 35 slowly rotates his hand about the shaft 25^a. This latter form of fine tuning can also be employed with the set of Figs. 1 to 4 if desired. In that case the operator would not press the knob 24 in, as shown in Fig. 3, but would merely rotate his 40 hand while the index finger is in the position shown in the depression 21^a of Fig. 2.

Thus it will be seen that a very simple yet efficient form of telephone type tuning dial is provided.

45 I claim:

1. In a radio receiving set, a tuning condenser, a tuning dial operatively connected thereto, said dial having a series of depressions adapted to receive the finger of an operator, and a knob mounted adjacent the dial so that when the operator's finger is in a depression, it can rest on the knob to assist in tuning. 5

2. In a radio receiving set, a tuning condenser, a tuning dial operatively connected thereto, said dial having a series of depressions adapted to 10 receive the finger of an operator, and a knob rotatably mounted adjacent the dial so that when the operator's finger is in a depression, it can rest on the knob to assist in tuning.

3. In a radio receiving set, a tuning condenser, 15 a tuning dial operatively connected thereto, said dial having a series of depressions adapted to receive the finger of an operator, and a knob rotatably mounted adjacent the dial so that when the operator's finger is in a depression, it 20 can rest on the knob to assist in tuning, the knob being operatively connected to the dial so that rotation of the knob rotates the dial.

4. In a radio receiving set, a tuning condenser, a tuning dial operatively connected thereto, said 25 dial having a series of depressions adapted to receive the finger of an operator, and a knob rotatably mounted adjacent the dial so that when the operator's finger is in a depression, it can rest on the knob to assist in tuning, the knob being 30 movable so as to be operatively connected to the dial so that rotation of the knob rotates the dial.

5. In a radio receiving set, a tuning condenser, 35 a tuning dial operatively connected thereto, said dial having a series of depressions adapted to receive the finger of an operator, and a knob rotatably mounted adjacent the dial so that when the operator's finger is in a depression, it can rest 40 on the knob to assist in tuning, the knob being movable endwise so as to be operatively connected to the dial so that rotation of the knob rotates the dial.

EDWIN G. BRADSHAW. 45
